UNITED STATES PATENT OFFICE.

JACOB J. NICHOLS, OF BROOKLYN, NEW YORK.

DESIGN FOR A GLOBE.

SPECIFICATION forming part of Design No. 13,336, dated October 10, 1882.

Application filed July 12, 1882. Term of patent 7 years.

To all whom it may concern:

Be it known that I, JACOB J. NICHOLS, of Brooklyn, in the county of Kings and State of New York, have originated a new Design for a 5 Globe, of which the following is a specification.

My design consists in making a globe of a shape to resemble a musk-melon, and with a number of upright convex projections.

The design also consists in making a globe 10 with a number of convex projections like those of a musk-melon, and having representations of ornamental objects delineated on such projections. Preferably the main portion of the globe will have a ground or frosted surface, 15 and the ornaments will be engraved or etched. The ornaments may be appropriately colored.

The accompanying drawing represents a side view of a globe embodying my design. This globe may be of any suitable height, either of 20 the taller or higher kind in use or of the squat pattern. It has around it a number of narrow convex projections, resembling in size and appearance those of a musk-melon. On these projections are delineated ornamental objects— 25 such, for instance, as flowers and leaves. The body or main portion of the globe will preferably have a ground or frosted surface, and the ornamental objects will be delineated by etch-

ing or engraving. If desirable, these representations of ornamental objects may be appropriately colored. This globe is designed 30 principally for use around gas and lamp burners, but obviously may be used for other purposes—as, for instance, for the bodies of lamp-fixtures.

What I claim as my design, and desire to secure by Letters Patent, is—

1. A globe having a number of convex projections, causing it to resemble a musk-melon, substantially as specified.

2. A globe having a number of convex projections, causing it to resemble a musk-melon, and having representations of ornamental objects delineated on such projections, substantially as specified.

3. A glass globe having a number of convex projections, causing it to resemble a musk-melon, and having representations of ornamental objects, the main portion of the globe, which constitutes the background for the objects, having a ground or frosted surface, substantially as specified.

J. J. NICHOLS.
